AUDITORIUM

Jules Ernest Varin, Neuilly-sur-Seine, France

Original application October 11, 1929, Serial No. 393,946. Divided and this application August 15, 1933, Serial No. 685,284. In France November 14, 1928

4 Claims. (Cl. 20—1,123)

This invention relates to the construction of theatres, cinemas, hospitals or the like, where the public are admitted in large numbers, to ensure efficient protection in the case of fire, both against the fire itself and against the panic, which is produced in such circumstances. The invention allows for limiting the material damage in the case of a serious outbreak.

This application is a division of my co-pending application filed October 11, 1929, Serial Number 393,946, and the priority of November 14, 1928 is claimed.

The invention is essentially characterized in that the floor of the hall, as well as all other galleries, open to the public, is supported by one or more columns which can be lowered in case of fire, in order to bring the said floor to ground level or underground, where very large exit doors may be provided along all sides, this lowering movement being carried out simultaneously with the positioning of a safety ceiling which takes the place of the floor, either by sliding or descending from above, so that the audience is protected during the lowering of the floor, and the damage limited whilst separating the upper part of the theatre which is stationary from the moving part.

It relates more particularly to a method of carrying out the invention, in which the movable part of the theatre is mounted on a nut, which can only move parallelly to itself without rotating, and inside which is mounted a hollow bolt which, during the lowering, rotates screwing itself up owing to the pressure exerted on the said nut, the movement of raising the floor being obtained by the expansion of a mixture of gases.

The whole of the installation may be connected by a mechanism operated for example by an electric switch (or in other manner) it being understood that the current should be taken from another main than that providing the light and power for the needs of the hall and the stage. In this way the audience will be taken out of danger in the space of five or six seconds without possible panic and above all without any one needing to leave their place during the very short time occupied by the operation.

This arrangement provided for the evacuation of halls where the public is received in large numbers may also be adapted to any private dwelling structure for the safeguard and security of the inmates, whatever the height of the structure and number of floors.

The invention will be described with reference to the accompanying drawing:

Fig. 1 is a longitudinal section.

Fig. 2 shows a modification for moving the separating wall into position.

According to the invention the floor *a* of the premises which carries all the seating space for the audience can be moved vertically without rotation to bring it to the ground level *b* where very large exits *c* are provided all around the building.

This movement, for lowering as well as raising, is carried out as follows:

The floor *a* is mounted on a nut *d* within which a hollow bolt *e* can rotate, this bolt *e* being connected at its lower end *f* to a stationary socket *g* forming a guide *h* for the vertical movement.

A pin *i* capable of being withdrawn in the direction of the arrow *j* by a cable from a windlass *k* against the action of a spring *l*, prevents the movement of the bolt *e*.

Columns *m* slide inside hollow pillars *z* on stationary rods *n* arranged around the periphery to guide the arrangement.

An aperture *o* which can be hermetically sealed by a valve *p* is provided for the introduction of a body *s* of dynamite for example into a chamber *q* having an upper cover *r*, this body *s* being capable of producing an intense gaseous dispersion when it enters into contact with an appropriate liquid *t* which is dropped upon it and which is contained in a reservoir *u*. This is provided at its lower end with orifices which can be opened or closed by a valve *v* to which is given a movement of 90°.

A baffle arrangement *w* centrally disposed as well as the length of the movable columns *m* (not shown in the drawing) prevents all possibility of this gas escaping except when the movable portions are in the raised position that is to say when the parts *x* provided in the hollow pillars *z* are uncovered by the columns *m*.

Stairs *y* rising from the ground level *b* give access to the floor *a* when it is in its raised or normal position.

A platform *2* sliding on slightly inclined runways *3* takes the place of the floor *a* when this is lowered.

In the modification shown in Fig. 2 this platform is in two parts *2* and *2'* and pivots into position on axes *13*.

Series of ball bearings or roller bearings *4*, *5*, *6* and *7* facilitate the displacement of the movable parts with respect to the stationary.

The operation of the arrangement is as follows:

When the chamber *8* is required to be rapidly cleared the windlass *k* is employed to remove the pin *i* which frees the bolt *e*. This latter owing

to the load which it carries commences to rotate in the direction of the arrow 9 whilst resting on the socket *g*, and the nut *d* and floor *a* are lowered until this latter reaches the ground level 5 *b*, from where the audience can be rapidly evacuated through the large doors *c*. Simultaneously with this lowering movement the movable platform 2 (either that shown in Fig. 1 or that shown in Figure 2) takes the place of the floor *a* so 10 that flames, plaster or slates cannot fall on to the audience during its descent. This platform limits at the same time the material damage if the fire develops.

To raise the floor into its initial position a 15 body *s* of dynamite for example is introduced into the chamber *q* the valve *p* closed and the handwheel *v* rotated to drop liquid *t* from the reservoir *u*. An intense cloud of gas is liberated the force of the expansion of which acts at 10 20 and 11 on the columns *m* and raises the floor *a*, nut *d* and bolt *e* into the higher position.

The bolt *e* rotating in the direction of the arrow 12 owing to its own weight comes in contact with the stop *r* when it is locked afresh by the 25 pin *i*. The gaseous products from the body *s* can only escape when the orifice *X* in the pillars *Z* are uncovered by the column *m*. An inspection cap 14 is provided for cleaning the chamber *q*.

This operation of cleaning can be assisted or 30 completely performed by means of one or more mechanical jacks or by a similar system of hand or electric jacks.

The movable platform 2 or 2¹ provided to take 35 the place of the floor *a* after this has moved may be in the form of a reservoir or suitable chamber into which is directed by nozzles suitably placed water or chemical products which will automatically extinguish any flaming material falling upon it.

40 As goes without saying and as a result of the foregoing the invention is not limited to the one means of operation described nor to the several parts but includes any mode of operation as well as the combination shown in the drawing.

45

What I claim as my invention and desire to protect by Letters Patent is:

1. An arrangement for the rapid evacuation of buildings in case of fire comprising a floor, a plurality of columns upon which the floor is mounted, a screw by which the floor is lowered, a pin for locking the screw in the raised position, a windlass for releasing the pin, doors surrounding the building at the ground level and movable platforms, the movement of which is controlled by that of the floor, for closing down into the position originally occupied by the floor. 80

2. An arrangement for the rapid evacuation of buildings in case of fire comprising a floor, a plurality of columns upon which the floor is mounted, a screw by which the floor is lowered, a pin for locking the screw in the raised position, a windlass for releasing the pin, doors surrounding the building at the ground level, and movable platforms, the movement of which is controlled by that of the floor, arranged for closing down into the position originally occupied by the floor. 85

3. A building having a vertically movable floor, guiding means for the floor, a fixed nut element 100 on the under side of the floor, a supporting screw for the floor engaged with the nut element, means by which the screw is mounted for free rotation under stress of the load of the floor whereby to cause the screw to permit the floor to be lowered 105 by gravity and means to lock the screw against rotation when the floor is in raised position and therefore cause the screw to support the floor in said position, said locking means being releasable from the screw. 110

4. In a building, a vertically movable floor, means to cause the floor to be lowered and a vertically movable platform or screen element above the floor and inclined runways for said platform on which said platform is slid able, said platform being controlled by the floor so that the platform is arranged to close the space above the floor when the floor is lowered. 115
